ABSTRACT OF THE DISCLOSURE

A constant current regulator in which a saturable magnetic core having a rectangular hysteresis characteristic is biased to negative saturation by a control current through a control winding with load current through a load winding opposing the ampere turns of the control winding. The load current flows to the load through a rectifier and saturates the core in a positive direction at the end of the load current cycle.

This invention relates to current stabilising devices.

It is known to employ magnetic amplifiers for the purpose of obtaining a stabilised or constant current output and for this purpose the magnetic amplifier is provided with a rather complicated external feed-back circuit by means of which constancy in current output is achieved.

It is an object of the present invention to provide a new and improved current stabilising device which does not involve the provision of such complicated circuitry.

If reference is made to FIG. 1 of the accompanying drawings which shows the characteristic of a conventional self-excited magnetic amplifier, it will be seen how this characteristic shows the variation of output current with control current for a fixed value of input voltage and load resistance.

With a normal self-excited magnetic amplifier the portion of a characteristic which is of most interest is the portion *b-c* wherein a substantially linear rise in output current occurs for relatively small changes in control current. It has been noticed, however, that with variation in the voltage or the load resistance the portions of curve *a-b-c* vary whilst the portions of the curve *c-d-e* remain substantially invariant.

This phenomenon has been utilised in the present invention by the design of an electromagnetic reactor having the construction of a magnetic amplifier but which is designed for operation in non-saturation conditions. Such a reactor will hereinafter be referred to as "an electromagnetic reactor of the kind specified." With an electromagnetic reactor of the kind specified particular advantage can be taken of the substantially invariant portion *c-d-e* whilst the other portions *c-b-a* can be virtually ignored.

According to the present invention therefore there is provided a current stabilising device comprising at least one electromagnetic reactor of the kind specified having an ampere-turn-ratio lying within the range of 0.5 to 10.

Preferably the ampere-turn-ratio is substantially equal to one.

With such a current stabilising device a substantially constant current characteristic is obtained within a very wide range of voltage and load variations when the or each reactor is operated with negative control current.

Current stabilising devices of the present invention will now be described with reference to FIGS. 2 to 4 of the accompanying drawings in which FIG. 2 is a schematic circuit diagram showing the use of a single leg reactor of magnetic amplifier construction as a current stabilising device.

FIG. 3 is a graphical representation of the current in the power or load circuit of the device of FIG. 2 plotted against the phase of the alternating voltage fed to the power circuit of the device, and FIG. 4 is a schematic diagram showing the use of a bridge type of reactor of magnetic amplifier construction as a current stabilising device.

The device of FIG. 2 includes a saturable reactor 1 comprising a control winding 2 and a power winding 3 wound on a suitable saturable core (not shown). A choke 4 is in series with the winding 2. Direct current voltage is applied to terminals 5 the polarity being as shown. The power winding 3 is connected in series with a rectifier 6 and a load 7 schematically represented as a resistance. The winding 3 is fed with alternating voltage applied to terminals 8.

If it is assumed that the magnetisation characteristic of the core approximates a rectangular or a square loop and that the inductance of the choke 4 is very high so that only a direct current can flow through the winding 2, it can be shown to first orders of approximation that the flow of current in the load circuit can be represented by the following equation:

$$i_a \cong -\frac{N_c}{N_a}(I_c + I_{cs})$$

where:

i_a is the average load current in the load circuit

N_c is the number of turns of the control winding 2

N_a is the number of turns of the power winding 3

I_c is the control circuit direct current

I_{cs} is the control circuit saturation current.

In the graph of FIG. 3 ωt is the phase angle of the alternating voltage $V = V_0 \sin(\omega t)$ applied to the terminals 8; A is the phase angle at the point in the cycle at which desaturation conditions occur in the core; and B is the phase angle at the point in the cycle at which the core is resaturated.

From the graph it will be seen that in the part of the cycle between the phase angles A and B the current flow through the winding 3 is substantially constant and the core is unsaturated. At the angle B the core resaturates. However, at this instant the rectifier 6 blocks and prevents the flow of saturation current so that the current flow rapidly drops to zero and remains at zero until the alternating voltage cycle recommences. In other words, when high ampere turns in the negative direction are present in the circuit of FIG. 2 it is possible to obtain a direct current flow which is not limited by the inductance of the winding 3 and which flows in the direction of rectifier conduction. The magnitude of this load current is given by the above equation and is not determined by the load resistance. This means that by operating the device shown in FIG. 2 in the unsaturated mode with a negative control current the device acts as a constant current device producing stabilised direct current from the alternating input fed to terminals 8. The extent of the unsaturated part of the cycle is determined by the magnitude of the saturation phase angle spread of A to B.

Since in practice A cannot be made equal to zero the circuit of FIG. 2 has limitations as regards efficiency.

The efficiency of the device is increased by effectively combining two of the devices of FIG. 2 to produce a bridge arrangement as shown in FIG. 4.

Referring to FIG. 4 there are shown two control windings 9 and 10 and two power windings 11 and 12. The control windings 9 and 10 and the choke 20 are connected in series with the control signal input terminals 13 to which are connected the positive and negative terminals of a control signal supply.

The two power windings 11 and 12 are connected in series with rectifier pairs 14, 15 and 16, 17, the alternating current power input being fed to terminals 18 which are connected to the power windings 11 and 12 in parallel. A lead 19 is connected across the power windings 11 and 12.

During each half cycle of the alternating voltage applied to the terminals 18 each reactor leg or winding pair 9, 12 and 10, 11, operates substantially as the arrangement of FIG. 2. However, an overlap in the cycles of operation of the two legs is caused by the fact that on reversal of phase the rectifier 16 through which "positive" current flows can pass the "negative" going current so long as its magnitude is smaller than that of the "positive" current. As the flow of current in winding 11 is limited by its resistance the current through the load circuit supplies ampere turns in opposition to the constant ampere turns in the control circuit so that by the time the rectifier 16 blocks the core of windings 10 and 11 is not saturated. This particular sequence of events in practice leads to an improvement in the constancy of the current output of the device of FIG. 4.

The electrical reactors of FIGS. 2 and 4 have been specifically designed so as to have ampere turn ratios substantially equal to one. It will be appreciated that with such a construction the arrangement is not suitable for use as a conventional magnetic amplifier and does not operate in the saturated region of the cores.

With the devices as described above it has been found that very constant current characteristics can be obtained within a very wide range of voltage and load resistance variations.

In an alternative circuit arrangement (not shown) a portion of the load current can be fed back to the control signal input to windings 9 and 10 so as to constitute at least a part of the control signal current.

It will be appreciated that whilst the invention has been specifically described with reference to a bridge con-

nection the invention is equally applicable to other reactor connections such as parallel, series, and multi-base connections.

What we claim is:

- 5 1. A constant current regulator comprising a saturable magnetic core having a first and second winding, a control current circuit, and a load circuit; said control circuit comprising a source of D-C current connected in series with said first winding; said load circuit comprising a source of A-C current, a diode and a load connected in closed series relation with said source of A-C current; said first winding being wound on said core whereby D-C current through said first winding tends to cause flux change in said core in a first direction; said second winding being wound on said core whereby current flow in the forward direction of said rectifier and through said second winding tends to cause a flux change in said core in a direction opposite to said first direction; said load current having a peak value equal to the product of the ratio of number of turns of said first winding to the number of turns of said second winding and the D-C current through said first winding; said ratio being in the range of from 0.5 to 10.
- 10 2. The device of claim 1 wherein said ratio is one.
- 15 3. The device of claim 1 which includes inductance means connected in series with said control circuit.
- 20 4. The device of claim 1 which includes feedback circuit means connected between said load circuit and said control circuit.
